(57) **CLAIM**

The ornamental design for a flushable sanitary wipe mitt, as shown and described.

DESCRIPTION

FIG. 1 is a distal end perspective view of a flushable sanitary wipe mitt in accordance with the present invention;

FIG. 2 is a proximal end perspective view thereof;

FIG. 3 is a first side view thereof;

FIG. 4 is a second side view thereof;

FIG. 5 is a left side view thereof;

FIG. 6 is a right side view thereof;

FIG. 7 is a distal end view thereof; and,

FIG. 8 is a proximal end view thereof.

The broken lines shown in FIGS. 1-7 illustrate lines of perforation and form no part of the claimed design.
